UNITED STATES PATENT OFFICE.

HERBERT AKROYD STUART, OF BLETCHELEY, ASSIGNOR OF ONE-HALF TO
CHARLES RICHARD BINNEY, OF LONDON, ENGLAND.

PETROLEUM ENGINE OR MOTOR.

SPECIFICATION forming part of Letters Patent No. 439,702, dated November 4, 1890.

Application filed May 29, 1889. Serial No. 312,609. (No model.)

To all whom it may concern:

Be it known that I, HERBERT AKROYD STUART, a subject of the Queen of Great Britain, residing at Bletchley, England, have invented 5 new and useful Improvements in Petroleum and other Hydrocarbon Explosive Engines or Motors, of which the following is a specification.

This invention relates to engines or motors 10 driven by the explosion of an inflammable mixture of the vapor of naphtha, benzoline, petroleum, or other hydrocarbon and air.

The said invention comprises improved means for controlling the flow or supply of 15 petroleum or other volatile liquid for the proper working of the engine or motor, improved means for vaporizing the volatile liquid, an improved firing or igniting valve, and improved mechanism for ejecting the products of combustion from the compression-chamber. 20

In the accompanying drawings, Figure 1 is a plan, partly in section, of an engine comprising my improvements; Fig. 1^a, a detail 25 of the switch-cam, and Fig. 2 is a sectional side elevation of the engine. Figs. 3, 4, and 5 are sectional views of the volatile-liquid-distributing, the vaporizing, and the igniting portions of the apparatus, respectively. Fig. 30 6 is a view similar to Fig. 4 of a modified form of vaporizer.

Similar letters of reference indicate corresponding parts in all the figures.

a is the bed-plate of the engine, and *b* is the 35 cylinder, which has the valve-chest *c* bolted thereon.

d is the working piston or trunk, which is connected by the rod *c* to the crank-shaft *f*, carrying the fly-wheel *g* and pulley *h*. 40

i is an auxiliary piston arranged at one end of the cylinder, forming a compression-chamber for clearing the products of combustion from the said chamber, the said auxiliary piston being normally kept in its innermost position within the cylinder by a spring *k*, located in a tube *k'*. 45

l is the induction-valve, through which the liquid and air for forming the combustible mixture are drawn, the said valve being kept 50 to its seat by a spring *l'*.

m is the oil valve or measurer for delivering the oil in quantities for the proper working of the engine, and it has a chamber *m'*, which is normally filled with air, preferably at atmospheric pressure, the said chamber being adapted to alternately make connection with the two passages *m*² *m*³, as shown in Fig. 3, which is a section of the said valve and the portion of the face upon which it works drawn to an enlarged scale. The passage *m*² communicates by a pipe *m*⁴ with a tank, in which a supply of petroleum or other hydrocarbon sufficient, say, for one or two days' working, is stored, which tank is placed several feet higher than the oil-measuring valve, so that the oil enters the valve-chamber *m'* at a pressure sufficient to compress the air therein, the quantity of oil entering the said chamber being in proportion to the compression of the air. The passage *m*³ extends from the valve-face to the induction side of the valve *l*. 55 60 65 70 75

n is a governor, which is driven from the crank-shaft through the medium of the gear-wheels *n'* *n*', the shaft *n*², and the gearing *n*³, and *o* is a cone, which is eccentrically mounted on the said governor. 75

p is a rod one end of which is secured to the valve *m*, the other end being shaped, as shown in Fig. 2, to bear against the side of the cone *o*, so that during the rotation of the said cone with the governors a reciprocating movement will be imparted to the valve *m*. A spring *p*', arranged upon the rod *p*, serves to move the valve outward after it has been moved inward by the cone. The speed of the governors is so regulated that no movement will be imparted to the cone in a vertical direction while the engine is running at its normal speed, so that at each reciprocation of the valves a supply of oil will enter the chamber *m'* from the passage *m*², and thence be carried to the passage *m*³. Should, however, the speed of the engine exceed its normal limit, the governors will expand and lower the cone, whereby the travel of the valve will be shortened (more or less) to limit or to entirely cut off the supply of oil from the passage *m*³. The object of admitting the oil into the chamber *m'* in such manner as to compress the air therein is for 90 95 the purpose of causing such oil to be quickly 100

injected from the said chamber m' when the latter is moved into connection with the passage m^3 .

q is a vaporizer, which is shown in Fig. 4 drawn to an enlarged scale, and which is placed in a chamber q' in the valve-chest c , which chamber is connected with the interior of the cylinder by a passage q^2 . This vaporizer is made of a good conducting metal, and, as shown, is surrounded by a series of troughs or cups q^3 , into which the oil passing through the valve l drops, the said troughs or cups being perforated to allow the passage of the oil. The said troughs or cups are also preferably loosely fitted upon the central tube q^4 , as shown in Fig. 4, so that they may be easily removed for cleaning or other purposes. The tube q^4 is open at the bottom and provided with a partition q^5 for causing the air to pass in a circuitous direction to the opening q^6 , which opening communicates by a pipe q^7 (shown in dotted lines, Fig. 2) with the space above the induction-valve l .

r is a three-way cock, which is inserted in the pipe q^7 and has one of its channels connected by a pipe r' with the exhaust, so that when desired the passage through the pipe q^7 to the space above the valve can be closed and that through the central tube of the vaporizer to the pipe r' and the exhaust opened.

s is a lamp, which, when crude or common petroleum is being used in the engine, is placed beneath the vaporizer for heating the same when first starting the engine, so that the oil delivered to the vaporizer is converted into vapor or gas. This lamp is not required, however, after the engine has been fairly started, as the heat of the combustion in the cylinder is sufficient to maintain the vaporizer at the required temperature.

t is the firing or igniting apparatus, which is shown drawn to an enlarged scale in Fig. 5, and which is placed in connection with the vaporizing-chamber q' through the passage t' , a valve t^2 being placed between the igniter and the vaporizer for controlling the admission of the inflammable mixture into the same. The valve t^2 is operated by the lever t^3 through the medium of the lever t^4 , hereinafter described.

The igniter is in the form of a tube containing a roll or wound sheet t^* of this good conducting metal, which presents a large heating-surface. This spiral is periodically subjected to the heat produced by the explosions in the cylinder, whereby it is heated sufficiently to fire the explosive mixture when it comes into contact therewith, the heat of the tube being maintained after the engine is set to work by the successive explosions therein. In order to prevent the vaporizer from becoming hot enough to fire the explosive mixture as it is being drawn into the cylinder I sometimes surround the same by a water-jacket.

u is the exhaust-valve, through which the products of combustion are discharged. This valve is normally held in its closed position

by a spring u' and is opened at the proper time by the lever t^4 , which bears against the under side of the same. The lever t^4 is operated by the switch-cam v , having two grooves v^1 v^2 arranged as shown most clearly in Fig. 1^a, which is a development of the same. The groove v^1 contains a raised cam-surface v^3 , and the groove v^2 contains a hollow or recess v^4 . The end of the lever t^4 carries a pivoted arm t^5 , having a roller t^6 , which runs in the grooves of the cam, which grooves are arranged in a well-known manner, so that the roller will run therein alternately, the mounting of the roller upon the pivoting-arm t^5 allowing the necessary lateral movement of the roller.

The operation of the apparatus hereinbefore described is as follows: Assume the piston d to be in close proximity to the piston i — that is to say, in the position which it occupies immediately after the products of combustion of an explosion have been discharged. The lamp is now placed beneath the vaporizer, so that the same is heated, and the three-way cock is turned so that the fumes from the lamp pass into the exhaust. At the outward stroke of the engine a supply of oil and air is drawn through the valve l and the vaporizer, (the said valve automatically opening under the influence of the vacuum produced in the cylinder,) whereby an explosive mixture is formed. On the return-stroke of the piston the mixture in the cylinder is compressed, the compression being sufficient to force back the auxiliary piston i to the cylinder-cover, at the same time the roller t^6 , which has been running in the groove v^2 , drops into the recess v^4 , so that the lever t^4 is operated to allow a portion of the inflammable mixture to enter the igniting-tube t , which ignitor must, when starting the engine, be heated by a lamp placed outside the same. The inflammable mixture being ignited in the ignitor, the flame is communicated through the passage t' , the vaporizing-chamber q' , and the passage q^2 to the cylinder charge, whereby the piston is forced outward. By this time the roller t^6 of the lever t^4 has entered the groove v^1 of the cam and been depressed by the projection v^3 , so that the said lever t^4 is operated to raise the exhaust-valve, whereby on the next return-stroke of the piston d the products of combustion will be forced out of the cylinder through the passage q^2 and the vaporizing-chamber q' . As the products of combustion in escaping pass through the vaporizer, the latter is heated, so that thereafter the lamp is rendered unnecessary. The three-way cock is also turned so that the air which enters above the valve l to form the explosive mixture passes through the pipe q^7 and the tube q^4 of the vaporizer, whereby it is heated before entering the cylinder. It will be obvious that when the exhaust-valve is opened the piston i is moved inward in the compression-chamber under the action of the spring k , whereby all the products of combustion will be discharged from the cylinder.

I wish it understood that I do not confine my improvements to the precise details of construction hereinbefore described, as it is obvious that the same may be modified

5 without departing from the nature of my invention. For instance, I sometimes employ a vaporizer of the kind shown in Fig. 6. In this modification the vaporizer instead of being heated directly by a flame when first starting the engine is heated by a liquid contained in a small receptacle *w*, the steam or other vapor generated rising into the vaporizer, the interior of which, in order to form a large heating-surface, is provided with shelves or 10 ribs *w'*. The liquid itself is heated by a lamp. After starting the engine the heat of the exhaust products is, as hereinbefore described, sufficient to maintain the temperature of the vaporizer.

15 20 When using a vaporizer of the kind shown in Fig. 6, the air for producing the inflammable mixture enters the cylinder without passing through the vaporizer.

Instead of providing the vaporizer with

trotights or rings, as described, I can, if desired, construct the same of metallic spirals or coils or the like.

I claim—

1. In a hydrocarbon engine or motor, the combination, with the firing apparatus consisting of a tube *t*, inclosing a roll of metal, of the vaporizer, the valve *t'* for alternately opening and closing the passage from the vaporizer to the firing apparatus, and means for actuating this valve. 25

2. In a hydrocarbon-engine, the described firing apparatus, consisting of the vertical tube *t*, closed at its top, and its inclosed roll *t'*, composed of a spirally-wound sheet of good conducting material, these parts being placed 30 in connection with the vaporizing-chamber, all substantially as set forth.

HERBERT AKROYD STUART.
